UNITED STATES PATENT OFFICE.

JAMES A. RAFFERTY, OF RYE, NEW YORK, AND HAROLD E. THOMPSON, OF CLENDENIN, WEST VIRGINIA, ASSIGNEES TO CARBIDE AND CARBON CHEMICALS CORPORATION, A CORPORATION OF NEW YORK.

PROCESS OF RECOVERING HELIUM.

Application filed June 15, 1923. Serial No. 645,672.

To all whom it may concern:

Be it known that we, JAMES A. RAFFERTY and HAROLD E. THOMPSON, citizens of the United States, residing at Rye and Cledenin, in the counties of Westchester and Kanawha and States of New York and West Virginia, respectively, have invented certain new and useful Improvements in Processes of Recovering Helium, of which the following is a specification.

The invention is a process for the separation of helium from gas mixtures. It will be described in connection with the recovery of helium from a natural gas containing such proportions of hydrocarbons that either the entire gas or the residue left after the helium extraction is adapted for use as fuel, but it will be understood that much of the procedure to be described is also applicable to gas mixtures of quite different composition; for example to natural gases containing so much nitrogen as to be of little or no use as fuels, and to mixtures containing helium with hydrogen or air or both and resulting from the intentional or accidental dilution of helium during its use for aeronautical purposes. Operating on a natural gas containing hydrocarbons but in too small quantities to fit the gas for use as a fuel, the process will produce, as a by-product, a combustible gas containing the hydrocarbons.

Only one plant capable of producing helium in quantities sufficient for aeronautical use has ever been set up, this being the Navy Department plant which is now in successful operation at Fort Worth, Texas. The present invention will be described as applied to the gas now treated at Fort Worth in order to show its advantages over the prior practice at that plant.

It will be recalled that the natural gas available at the Fort Worth plant comprises a large percentage (roughly 70%) of hydrocarbons, mostly methane. Since methane boils at about -165° C. at 760 mm. pressure and the other hydrocarbons present have higher boiling points, and since helium and nitrogen are the important non-hydrocarbon constituents of the gas, it is convenient to consider the hydrocarbons collectively as a relatively non-volatile fraction of the gas. It should be noted that the gas

is treated for gasoline-extraction before it reaches the helium plant and hence is almost free from butane and less volatile hydrocarbons. The process and apparatus to be described are designed for the treatment of a material which does not contain more than small quantities of gasoline constituents, and well-known processes may be preliminarily applied, where necessary, to secure this condition.

Helium resists liquefaction more strongly than any other known gas and hence is easily the most volatile material in the natural gas. Hydrogen is absent from the gas, and nitrogen, boiling at about -193° C. under 760 mm. pressure, stands next to the helium in relative volatility. The nitrogen content of the natural gas is roughly 30%, the helium constituting less than 1%.

Gas of the foregoing composition is received at the plant by pipe-line under a pressure which fluctuates somewhat but rarely or never falls below 10 atmospheres. The former practice included an initial expansion of the gas to substantially barometric pressure without utilization of the energy represented by the pressure on the gas. Since several million cubic feet of gas were treated daily, a very considerable energy loss was sustained in this way.

The gas was then scrubbed with a solution of an alkaline substance, such as lime-water, to reduce the carbon dioxide content in order to prevent the clogging of the helium apparatus by congelation of the carbon dioxide.

A portion of the gas was then compressed to about 6 atmospheres, the rest of the gas being brought to a much higher pressure, usually considerably in excess of 100 atmospheres. Both portions of compressed gas were cooled, eventually by heat-exchange with waste gases, and passed to a column, the mixture passed through a series of progressively decreasing temperatures for the separation of successive fractions of the hydrocarbons and the nitrogen.

During this stage of the process, the natural gas undergoing treatment was held at about 6 atmospheres. The expansion to this pressure of the cooled high-pressure portion of the natural gas furnished most of the refrigeration required in the process.

The last condenser of the series just described, operating at about 6 atmospheres internal pressure, was cooled with substantially pure liquid nitrogen provided by an auxiliary cycle. Two other condensers at higher temperatures were used, an intermediate condenser cooled by the reflux from the last condenser, and another condenser cooled by the reflux from the intermediate condenser and hence operating at the highest temperature of all. In addition, a large amount of material was liquefied before the first condenser was reached, at the expansion of the high-pressure gas.

With pressures of only 6 atmospheres within the condensers, it was necessary to permit the cooling liquids surrounding them to boil at substantially atmospheric pressure in order to get temperatures low enough to effect the desired amount of liquefaction within the condensers. As a result, practically all of the natural gas treated was expanded to atmospheric pressure to secure sufficient cooling, and had then to be brought up to about 17 atmospheres for transportation through a pipe-line to the place of use. The compression just described was the second to which all of the gas passing through the plant was subjected, and in each instance the compression was from atmospheric pressure.

The series of steps just described produced a helium concentrate containing usually about 60% helium, though about 75% was theoretically possible under optimum conditions. This concentrate, containing only helium and nitrogen, was then expanded to atmospheric pressure and allowed to warm up to atmospheric temperature. This concentrate was then compressed to about 70 atmospheres and cooled to the temperature of boiling nitrogen, whereupon sufficient liquefaction of nitrogen was brought about in the helium concentrate to increase the helium content to 95% or more.

In accordance with our invention, the process described above has been so modified that the power consumption is greatly reduced. Helium which is of higher purity may also be produced, and by the addition of steps which have no counterpart in the prior process, the helium content can be so increased that impurities are either entirely negligible or absent. The process is also improved in several other respects, notably in the greater ease with which the desired temperatures and pressures, and hence quality and quantity of helium produced, can be maintained.

The invention will now be explained in connection with the accompanying drawing, in which—

Fig. 1 is a series of curves showing the theoretical helium content or "test" at various pressures (plotted as abscissæ) and

at three different temperatures, all readily obtainable by the evaporation of liquid nitrogen at or near atmospheric pressure;

Fig. 2 is a curve showing the reduction in helium test which follows an increase of temperature from -190° C. to -185° C., at various column pressures;

Fig. 3 is a diagrammatic representation of our improved process; and

Fig. 4 shows an auxiliary purifier containing activated carbon.

Figs. 1 and 2 show strikingly the reason for certain instabilities in operation which were encountered in the prior process. In Fig. 1, the prior operating pressure of 6 atmospheres is on the steeper portion of each curve, so that the effect of any inadvertent variation in pressure is to alter the test of the outlet helium concentrate materially. Similarly, Fig. 2 shows that even a slight increase in condenser temperature, such as may result from a slight contamination of the nitrogen bath with methane, will seriously affect the test of the helium.

In accordance with our invention, the operations formerly carried out under a pressure of about 6 atmospheres are conducted at higher pressure, corresponding to a point beyond the knee of any of the various curves in Figs. 1 and 2. In this region, all the curves have relatively low slopes, and the effect of fluctuations in temperature and pressure is considerably mitigated.

As less and less advantage is obtained by successive increases in pressure, it will be seen that a practical pressure limit is soon reached. We have found that a working pressure of about 22 atmospheres gives considerably better results in the respect just discussed than does the former pressure of 6 atmospheres.

The use of such a pressure as 22 atmospheres is even more advantageous in other respects. The test of the helium passing to the last condenser can be raised from about 60% to about 90%, without the use of lower temperatures than before. In fact, certain of the condensers may be held at considerably higher temperatures than formerly, these higher temperatures being such as those produced by boiling liquids of composition similar to those formerly used, but at pressures approximating 17 atmospheres instead of the substantially atmospheric pressure formerly maintained. This latter gives rise to a principal advantage of our invention, in that the gas produced by the abullition of these liquids is at a sufficient pressure to enter the pipe-line without any work being done on it after it has been used for cooling.

The curves of Fig. 1 also show that the final condensation of impurities from the impure helium, formerly conducted at about 70 atmospheres, can be carried out at very

much lower pressures, even at the 22 atmospheres used in the earlier stages, and a higher test helium nevertheless produced, provided a temperature only a little lower than that now employed is maintained at the condenser. Such a temperature is readily attained by evaporating nitrogen under a partial vacuum, say at about one-half atmosphere absolute pressure.

10 Our preferred arrangement for the complete process is shown in Figs. 3 and 4, and is as follows:

The helium-bearing gas, previously deprived of its gasolene constituents, and arriving at the plant through a pipe-line 1, at or above 10 atmospheres pressure, is scrubbed at that pressure in scrubber 2 for the removal of carbon dioxide. Owing to the increased solubility of carbon dioxide at such pressures, water alone acts as a very effective agent for removing carbon dioxide. If a more complete removal of carbon dioxide than can be obtained with water alone is desired, the gas may be passed to a second scrubber 3, where it is treated with a solution of an alkaline substance such as lime water. The absorbent action of lime water is also increased by the pressure.

From scrubber 3 a portion of the gas passes through line 4 to low pressure compressor 5 where its pressure is brought to about 23 atmospheres. The compressed gas passes through a fore-cooler 6 refrigerated by an ice machine 7, and thence through line 8 to the main heat-exchanger.

Another portion of the helium-bearing gas, after removal of the carbon dioxide, is drawn through line 9 to high pressure multi-stage compressor 10, and is brought to about 135 atmospheres. The high pressure gas passes through a fore-cooler 11 refrigerated by an ice machine 12, and is carried through line 13 to the main heat-exchanger, but is kept separate therein from the low pressure gas entering through 8.

The high pressure gas emerges from the heat-exchanger through line 14, whence it passes to coil 15 immersed in a bath of boiling liquid at low temperature. After its final cooling in this coil, the high pressure gas expands through valve 16 into the column at a point below condenser A. The low pressure gas leaves the heat-exchanger by line 17, passes through a coil 18 likewise immersed in a low temperature bath of boiling liquid, and then flows through line 19 and valve 20 to the same column into which the high pressure gas is expanded.

The expansion of the cooled high pressure gas to the column pressure, about 22 atmospheres, absorbs a large quantity of heat. The less volatile constituents of both high and low pressure gas, for example the propane, most of the ethane and some methane, are condensed, flow down through the

column where they are subjected to rectification to remove any dissolved helium, and collect in the kettle containing the coil 15.

Those constituents of the gas which are not liquefied on expansion, and including all the helium of the gas, pass upwardly through the column to condenser A, where they are subjected to the temperature of the liquid boiling about the condenser, this liquid being held under a pressure of about 17 atmospheres. A further quantity of relatively non-volatile material is liquefied in condenser A and returns to the column below, in which it also is rectified.

The helium and other gases not liquefied in condenser A pass through line 21 to a column which is surmounted by condenser B. Condenser B is surrounded by a boiling liquid which is held at the same pressure as that which obtains about the condenser A, but the liquid surrounding condenser B contains more of the volatile constituents of the natural gas, such as nitrogen and methane, and hence is at a lower temperature than the liquid about the condenser A. As a result, an additional quantity of material is liquefied in condenser B and descends through and is rectified in the column immediately below, collecting finally in the kettle 22 in which is contained the coil 18 previously referred to.

The helium, still admixed with many times its volume of gaseous impurities, leaves condenser B through line 23 and enters the column which is immediately below condenser C, the helium-containing mixture being still at the same pressure of 22 atmospheres. Condenser C is cooled by substantially pure liquid nitrogen boiling at about atmospheric pressure, and hence the temperature of condenser C approaches closely the boiling point of nitrogen, -193° C. As this temperature is considerably below the temperatures of condensers A and B, a further quantity of the gas associated with the helium, now chiefly nitrogen, is condensed, and passes down through the column immediately below, where it is rectified to remove any dissolved helium. The liquid collects in kettle 24 at the bottom of the column and there surrounds and cools coil 25, which performs the function presently to be described.

Due to the temperature and pressure prevailing in condenser C, a helium concentrate containing about 90% of helium will be produced. This concentrate passes through line 26 to the final condenser D where it is subjected, still at a pressure of about 22 atmospheres, to the temperature of nitrogen boiling under reduced pressure, say at about one-half atmosphere absolute. This will give a temperature below -195° C. in condenser D, and as a result some of the small amount of residual nitrogen will be lique-

fied and a concentrate containing about 98% helium, and usually considered pure enough for aeronautical purposes, will pass the condenser, expand through valve 27, and 5 pass through line 28 to the helium holder 29.

The arrangement for producing the nitrogen baths which surround condensers C and D will now be described.

Nitrogen is drawn from holder 30 and 10 compressed in multi-stage compressor 31 to a pressure of about 135 atmospheres. The compressed gas then passes through fore-cooler 32 refrigerated by the ice machine 33, and thence through the nitrogen heat-exchanger. The cooled high pressure nitrogen emerges from the heat-exchanger through line 33* and passes through coil 25 previously referred to, where it is brought 15 into thermal contact with the very cold boiling liquid in kettle 24. The liquid in kettle 24, it will be noted, is under a pressure of about 22 atmospheres. The nitrogen now passes through coil 34 disposed in the bath around condenser C and hence immersed in 20 nitrogen boiling at or a little above atmospheric pressure.

After this final cooling the nitrogen expands through valve 35, which results in its 25 partial liquefaction. The liquid nitrogen collects about coil 34 in condenser C, where it boils away continuously and produces the refrigerating effect already referred to. The gaseous nitrogen produced by the boiling of this bath passes at slight pressure 30 through line 36 to the nitrogen heat-exchanger, where it cools the high pressure nitrogen and then flows through line 37 to the nitrogen holder 30.

The space around condenser D is held, as 35 already stated, under a partial vacuum. Liquid nitrogen will rise at a regulated rate through valve 38 and collect about condenser D, boiling there under the reduced pressure at a very low temperature. The gaseous nitrogen produced by the boiling of this liquid passes through line 39 to another section of 40 the nitrogen heat-exchanger, where it assists in the cooling of the high pressure nitrogen, and then passes through line 40 and vacuum pump 41 to the nitrogen holder. The small quantity of liquid formed in 45 condenser D and consisting of pure nitrogen, returns through the trap 42 to the top of the column surmounted by condenser C.

The gases produced by the boiling liquids around condensers A and B pass through lines 43 and 44 respectively to the main heat-exchanger, where they cool the high and low pressure helium-bearing gas, and then pass through lines 45 and 46 respectively to a receiver which discharges helium-free gas into a pipe-line to be transported to the place of its consumption. Since the baths about condensers A and B are maintained at 17 atmospheres pressure, and the reverse flow

passages of the main heat-exchanger are at the same pressure, the exit gases may enter the line without being further compressed. A portion of the liquid contained in the kettle around coil 15 is also continuously withdrawn through line 47 to the main heat-exchanger, in which it evaporates and assists in cooling the high and low pressure helium-bearing gas, passing from the heat-exchanger through line 48 to the receiver and pipe-line already referred to. The exit gases passing through the main heat-exchanger and lines 45, 46 and 48, constitute practically all the natural gas entering the plant with the exception of the helium. 70

The condenser B is cooled by liquid which collects in kettle 24, and flows through line 49 and valve 50 into the space surrounding condenser B. Condenser A is similarly cooled by liquid which collects in kettle 22 85 and flows through line 51 and valve 52 to the space surrounding condenser A. At valves 50 and 52, the pressure on the liquids just referred to is reduced from about 22 atmospheres to about 17 atmospheres. 90

Should it be desired to remove from the helium leaving condenser D the very small quantity of impurities contained in it, the apparatus shown in Fig. 4 may be used being introduced into the system at an appropriate point, for example between condenser D and the helium holder. 95

This apparatus consists of a series of identical absorbers comprising an inner chamber packed with activated carbon 53 held between foraminous partitions 54. To facilitate the absorption of the impurity (nitrogen) in the carbon, the latter should be cooled to a very low temperature and we have shown the absorbers provided with jackets 100 55, through which may be passed a very cold medium, such as nitrogen from the space around condenser C. The absorbers may be small, as they are designed to take up an impurity which constitutes only about 2% of the helium, the helium being less than 1% of the gas treated. 105

When cooled to a temperature such as that indicated, activated carbon selectively absorbs the impurity with great efficiency, and the purity of the helium can be raised to any desired value. When one absorber is saturated to the desired degree with impurity, it is cut out of both the helium and the refrigeration circuits and allowed to 110 warm up to room temperature, whereupon the absorbed impurity will pass off through 115 56. The absorber is then ready for use again as soon as it has been cooled to the required low temperature. 120

The advantages of our invention over the prior process may be summarized as follows:

The gas treated is compressed only once, 125 and from a pressure of 10 atmospheres, 130

whereas in the prior process all the gas was compressed twice, and each time from atmospheric pressure, while the 60% helium concentrate was additionally compressed from atmospheric pressure to 70 atmospheres. As a result, fewer compressors are required and less power is consumed.

10 Helium of greater purity is produced even without the activated carbon absorber. The latter, at the low temperature used by us, affords a means for securing helium of any desired purity.

15 The carbon dioxide may be removed from the gas more effectively, in smaller apparatus, and with a cheaper reagent. Less water will be taken up by the gas during the removal of the carbon dioxide, giving a better operation of the gas coolers.

20 The main heat-exchanger and condensers A, B and C, and all passages for gaseous material, can be smaller, as the gas is considerably reduced in volume by the higher pressure. It is true that the gas passing through condenser D is at lower pressure than in the final 70 atmosphere condenser of the prior process, but only about 1% of the gas treated flows through this condenser. Furthermore, the purity of the helium passing to D is much higher than 30 in the former process, so that condenser D treats less gas than before.

The process is less sensitive to changes in operating conditions.

35 The saving in power consumption in the new process is estimated at 45%.

40 As already stated, the gas mixture passing through condenser C will contain as high as 90% helium. In other words, the temperature and pressure conditions prevailing in the condenser are such that the partial pressure of the impurities does not exceed 10% of the total pressure. Our invention is not limited to this condition, however, and we regard as within our in-

vention all methods of operation wherein with a temperature not below -193° C. there is applied a pressure sufficient to cause the partial pressure of the impurities to be not more than 20% of the total pressure.

In our novel process, all the principal 50 cooling baths are held at such pressures as will permit of the gases produced by their ebullition being introduced directly into the pipe-line. Any usual pipe-line pressures, for example 10 to 20 atmospheres, are 55 adapted for use in our invention at the points referred to, and are covered in the appended claims.

Having now described our invention, we 60 claim:

1. Process of producing a helium concentrate from natural gas which comprises liquefying a portion of the gas, holding the liquid so produced under a pipe-line pressure, and cooling another portion of the gas under higher pressure therewith, said higher pressure being such that partial liquefaction of the portion so cooled will result.

2. Process of producing a helium concentrate from natural gas which comprises 70 progressively cooling the gas by means of liquefied fractions thereof boiling at a pipe-line pressure, while holding the gas to be cooled under sufficient pressure to liquefy non-helium constituents thereof.

3. Process of producing a helium concentrate from natural gas which comprises the successive steps of compressing, cooling, and expanding the gas to liquefy a portion thereof, leaving a gaseous residue; and liquefying a portion of said residue by transferring heat therefrom to natural-gas constituents held at pipe-line pressure.

In testimony whereof, we affix our signatures.

JAMES A. RAFFERTY.
HAROLD E. THOMPSON.
